(57) **CLAIM**

The ornamental design for a yard tool cart, as shown and described.

DESCRIPTION

FIG. 1 is a front elevational view of the yard tool cart of the present invention, the rear view being a mirror image thereof;

FIG. 2 is a left side elevational view of the yard tool cart of FIG. 1;

FIG. 3 is a right side elevational view of the yard tool cart of FIG. 1;

FIG. 4 is a top plan view of the yard tool cart of FIG. 1; and, FIG. 5 is a bottom plan view of the yard tool cart of FIG. 1. The hollow interior of the cart as shown through the holes in FIG. 4 is plain and unornamental and forms no part of the claimed design.
